DESIGN.

O. HEINIGKE.

CARPET.

No. 17,251.

Patented Apr. 12, 1887.

UNITED STATES PATENT OFFICE.

OTTO HEINIGKE, OF NEW Utrecht, NEW YORK, ASSIGNOR TO THE HART-FORD CARPET COMPANY, OF HARTFORD, CONNECTICUT.

DESIGN FOR A CARPET.

SPECIFICATION forming part of Design No. 17,251, dated April 12, 1887.

Application filed February 18, 1887. Serial No. 228,124. Term of patent 3½ years.

To all whom it may concern:

Be it known that I, OTTO HEINIGKE, of New Utrecht, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet, showing my new design.

15 The main feature of the design is the figure A. The figure A is of general hexagonal outline, slightly elongated, and has four large indentations on each side, making the figure as a whole resemble a leaf figure with small stem 20 below and lobes on each side. Centrally located on this figure A, and forming a part of it, is a key-work ornamentation consisting of a

central stem and symmetrically-arranged keys or key-work springing upward and outward from the central stem, and in general direction corresponding to the general direction of the lobes formed by the outlines of the figure. This figure A is repeated, as shown, and the spaces between the figures are occupied by an inconspicuous chain-work or net-work of small figures, which surround and frame the figure A, forming a ground.

What I claim as new, and desire to secure by Letters Patent, is—

1. The design for carpets, consisting of the figure A, substantially as shown and described.
2. The design for carpets, consisting of the figures A and the frame-like ground, substantially as shown and described.

OTTO HEINIGKE.
